United States Patent Office

Des. 234,022
Patented Dec. 31, 1974

234,022

COMPUTER MAINFRAME CONSOLE

Seymour R. Cray, Lester T. Davis, and Maurice D. Roush,
Chippewa Falls, Wis., assignors to Control Data Corporation,
Minneapolis, Minn.

Continuation-in-part of design application Ser. No.
341,429, Mar. 15, 1973. This application Apr. 30,
1973, Ser. No. 355,997

Term of patent 14 years

Int. Cl. D14—02

U.S. Cl. D26—5 C

FIG. 1

FIG. 2

FIG. 3

FIG. 1 is a perspective view of a computer mainframe console, showing our new design;

FIG. 2 is a front elevational view thereof; and

FIG. 3 is a top plan view thereof.

This application is a continuation-in-part of design application Ser. No. 341,429, filed Mar. 15, 1973.

The sides and rear of the computer mainframe console have the same appearance as the frontal view.

We claim:

The ornamental design for a computer mainframe console, as shown and described.
